WELT INSOLE AND PREFORMED SEWING
RIB THEREFOR

Wallace C. Wright, Brookfield, N. H.

Application March 17, 1943, Serial No. 479,528

4 Claims.

(Cl. 36—23)

My present invention is a novel and improved welt insole for use in the manufacture of boots and shoes, and is directed more particularly to an improved sewing rib incorporated with said insole.

Heretofore in the manufacture of welt shoes, it has been customary to utilize an insole which is of sufficient thickness, or "irons," to enable the edge portion to be split and a part of the insole to be turned upwardly to constitute a sewing rib or a part of such rib, and usually a channel was cut in the insole opposite the split portion, and the channeled part also turned up and incorporated in the sewing rib for stitch-retaining strength.

Other efforts to utilize a sewing rib in an unchanneled insole were to secure to the marginal edge of an insole blank a flanged tape, preferably enclosing a filler, and stitched or adhesively secured together. The welt insole was then tacked to the bottom of the last and the upper materials assembled, lasted, and secured to the insole by tacks or to the sewing rib by staples, and thereupon the inseam stitching was applied, uniting the sewing rib, upper materials, and welt together.

In this prior practice it was difficult, if not impossible, to have the upper materials, viz., upper and lining, snugly in contact with the sewing rib throughout its length, even when the inseam stitching was set under considerable tension, as the upper would span the space between the outside edge or feather of the insole and the top of the rib, thus leaving a highly objectionable groove or space at the base of the rib.

This prior construction rendered it difficult to have a good, close, and tight-fitting seam and permitted the stitches to "grin" because of the looseness at this point.

My present invention has for a prime object to obviate the difficulties above briefly outlined and to provide a sewing rib structure which will be accurately preformed for "streamline" attachment of the upper materials thereto, assuring snug and close contact of the upper materials to the rib throughout the entire height of the rib, thus eliminating the objectionable open groove or space heretofore found in welt footwear.

A further object of the invention is to provide a sewing rib construction which will be accurately preformed to facilitate lasting and inseaming, and to provide a proper angle or surface of substantial strength and rigidity to receive stapling and inseam stitching, the latter being usually set by a curved needle.

For the purpose of increasing the tightness of the seam and to facilitate the curved needle sewing, I provide a novel form and type of rib structure which can be secured to an insole blank adjacent the margin and with a predetermined inner bevelled or angular face to insure the stitching lying at the base of the rib, and with the opposite or outer surface of the rib at a predetermined angle to facilitate the penetration of the curved needle during the inseam stitching, and also with a portion of the rib of a contour to facilitate lasting and stapling.

In carrying out my invention, I provide a sewing rib with an attaching flange, preferably, of a mass of integral homogeneous material, such as either a molded or extruded plastic, which may be of continuous length and of predetermined contour, thickness, strength, and permanent resiliency, and can be readily attached to the marginal portion of the insole blank by adhesive or mechanical means. I find that standard types of material such as Koroseal, Vinylite, or the like can be used advantageously for this purpose. By utilizing material of this type I am enabled to accurately preform the outer and inner surfaces of the opposite faces of the rib and because of the novel contours accorded for stapling and stitching, I can utilize a relatively low rib in height, as the surface contours insure and facilitate accurate lasting, stapling, and stitching. This also serves to eliminate to a large degree the trimming and waste material on the rib when the subsequent inseam operation is performed on welt footwear.

The outer edge surface of my novel rib has a fillet or extending flange-like contour projecting toward or adjacent the outer edge of the insole to which the rib is attached, thus permitting the upper materials to be snugly drawn into contact with the entire vertical surface throughout the height of the rib, including the curved fillet, and facilitating also a better and tighter fitting of the welt, eliminating completely the objectionable space or groove heretofore existing between the outer edge of the insole, the outer surface of the sewing rib, and the upper materials. This fillet is an important feature and enables the sewing rib to be positioned more closely adjacent the edge of the insole than heretofore, if desired, as well as enabling the rib to be spaced from the edge and still enable a snug and tight-fitting of the upper thereto.

I also prefer to form the upper part of the outer vertical face of the rib throughout its length in a position substantially perpendicular

with the plane of the insole to which the rib is attached to facilitate the stapling. Furthermore, I make the inner upstanding surface of the rib at an angle less than 90° relatively with the surface of the insole, thus giving an acute angled or bevelled surface to insure the inseam laying at the base of the rib and, furthermore, providing a considerable mass throughout the height and thickness of the sewing rib to withstand the lasting and stapling strains and give a substantial mass of material to which the upper is secured.

Thus it will be appreciated that my novel insole with the sewing rib having an inner acute angled bevelled face, and an outer face in the form of a combined fillet or curve at the bottom, and a substantially perpendicular upper face, produces a rib with a broader mass of material widthwise at the top than at the bottom to secure the desirable results above briefly outlined. This feature of having the inner and outer vertical faces of the sewing rib at a relatively divergent angle so as to be broader at the top is a distinct novelty, as far as I am aware; and the further feature of having the outer vertical face formed with a portion as a fillet or curved, straight, or sloping flange-like element, with the upper portion of the face of the sewing rib at a proper and ideal angle for inseaming and stapling, as well as providing a firm but initially and permanently yielding rib structure to insure proper resistance to lasting and guiding of the lasting, are believed to be novel, and I wish to claim these features herein broadly.

Referring to the drawing illustrating a preferred embodiment of the present invention:

Fig. 1 is a perspective view partly in cross-section showing my novel type of sewing rib on an enlarged scale;

Fig. 2 is a fragmentary view in cross-section of a side portion of the insole with my sewing rib attached adjacent the margin;

Fig. 3 illustrates in fragmentary view an insole on a last, with the upper and lining stapled to the sewing rib;

Fig. 4 is a corresponding view showing the inseaming attaching the welt, and

Figs. 5 and 6 are diagrammatic views in cross-section illustrating prior sewing rib structures to distinguish over applicant's improved and streamlined outer face with the diverging side faces on the rib.

Referring to Fig. 1, my sewing rib designated generally at 1 is preferably formed of a mass of permanently plastic material, such for example as numerous well known types of synthetic polyvinyl resins, which may be molded or extruded, and of a suitable consistency and toughness to be stitch-retaining. I find that Koroseal, Vinylite, and similar materials may be utilized from which to make my novel preformed rib.

Preferably I also form integral with the sewing rib 1 a horizontal attaching flange 2, in order to facilitate the adhesive attachment of the rib to an insole blank 3. This attaching flange 2 may be and preferably is formed as a double rib structure, with a series of zig-zag curves or lines, cutting the two rib portions apart, forming each as a separate rib structure, with the attaching flange "pinked" as shown. The outer face of the rib has two surfaces, the lower curved or fillet portion 5 and an upper vertical, or substantially vertical, face 6; and the opposite or inner sloping face 7 is preferably formed at an acute

angle relatively with the horizontal flange 2, thus giving a flaring or divergent structure to the rib in cross-section, with a substantial mass of material at the top. This gives added strength and resistance during lasting and stapling even though the rib itself is of pliable, permanently resilient material, such as the synthetic plastics above mentioned.

Preferably the rib is attached to the marginal portion of the insole with a fillet or curved part 5 adjacent or even in register with the extreme edge 8 of the insole, as shown in Fig. 2, thus giving a much closer and tighter edge to the insole and the resilient shoe structure than has heretofore been possible where a standard type of channeled or composite built sewing rib has been utilized, which latter types are shown in diagrammatic form in Figs. 5 and 6 for illustration. The fillet 5 may, of course, be either curved or straight as a part of the outer surface of the rib.

With the insole assembled on a last 10 and the upper materials 11 and 12, viz., a lining and finished upper, the shoe is lasted in the usual manner and stapling or lasting fasteners 14 are applied thru the upper and rib, the width and strength afforded by the mass of the rib constituting a good firm guiding element against which the lasting operation can be held and the stapling or other mechanical fasteners secured. Thereupon the welt is fitted and applied, and the inseam stitching 20, which latter draws the upper firmly against the fillet portion 5, thereby giving a firm solid bearing between the welt, upper materials, and sewing rib, and a contact of the upper substantially against the entire outer face of the sewing rib 1. The inner inclined surface 7 and the relatively wide and solid face of the sewing rib gives a firm and accurate guide for the inseaming machine during the seating of the inseam stitches 20, thus insuring a tight joint, better fitting, and good shoe-making, eliminating grinning of stitches along the forepart and toe of the shoe.

In Fig. 5 I have illustrated in fragmentary form a typical channeled insole 21 with the edge portion split and turned up into a rib member 22, and with an inner channeled lip or rib 23 also cut and turned and joined together into a sewing rib against which the upper materials 24 and 25 are lasted and stapled. Owing to the length required to make the rib members 22 and 23, the rib itself is a substantial distance back from the edge 26 of the insole, thus leaving a feather 27 and thereby also tending to leave an open channel or groove 30 throughout the entire length of the ribbed structure.

It is this channel or groove which is an object of my invention to eliminate. Such a rib is usually reinforced or gemmed by a strip of canvas 28, and the inseam stitching 31 draws the upper materials partly into and against the sewing rib but necessarily tends to leave an open space or channel 30, as above explained.

Similarly in Fig. 6 I have illustrated a prior rib structure comprising a fragmentary portion of the insole 33 and the sewing rib built of a filler 34 and a overlapping double flanged member 35, with flanges 36 and 37 secured to the face of the insole 33 by adhesive, stitching, or the like.

In this form, also, the upper materials 38 and 39 will tend to leave an open space or groove 40 at the base of the rib, which is objectionable. Both these prior constructions also required con-

siderable trimming and cutting away after the inseaming; whereas in my relatively low and broad resilient sewing rib, the inseam trimming, as indicated at A—A Fig. 4, removes and hence wastes only a slight amount of the plastic material constituting the rib 1. Also, my lower rib structure, with the diverging upstanding sides or faces, enables a considerably lower rib to be used and, hence, less filler in the shoe between the insole and outsole is needed.

My invention of a preformed sewing rib structure having an upstanding rib portion, with an inwardly slanting surface, i. e., inwardly toward the center of the insole to which the rib is attached, to facilitate the inseam stitching and guiding, together with the outer or opposite side face of the rib extending substantially perpendicular and, hence, at a divergent angle with the inner slanting face, and thus producing a somewhat flaring top thickness in the rib, is a distinct novelty in this art and I wish to claim the same herein broadly.

Also the preforming of such a molded rib structure with the opposite faces of the side walls from a mass of plastic material having initial and permanent resiliency, together with toughness for stitch-retaining and sufficient strength to resist the lasting operations, stapling, or tacking and inseaming, is believed novel and is claimed broadly herein.

Also the fillet feature, permitting the sewing rib to be secured closely adjacent the edge of the insole, as well as at spaced or variably spaced positions throughout the forepart and toe portions, and heel if desired, provides an effective "streamlining" for snug and close fitting of the upper materials and welt, which are drawn into close contact with the fillet and rib during the inseaming operation. Heretofore, upstanding sewing ribs have usually had the side faces parallel and if the rib was slanted inwardly toward the center of the insole, as was desirable, the outer surfaces of the rib would also slant inwardly, resulting in difficulty in lasting and stapling, and tending to looseness in the inseam stitching, which resulted in the stitches "grinning," as above explained.

My present invention includes a relatively strong, stapling and stitch-retaining upper portion on the sewing rib because of the flaring structure, the greater mass and thickness, and the plasticized resinous material, such as Koro-seal or Vinylite above mentioned.

Thus my preformed rib is self-sustaining and stitch-retaining independently of gemming or reinforcing strips or tapes, which latter are necessary where any rubber compound is employed and, of course, rubber quickly loses its strength and resiliency; whereas the synthetic resinous material such as Koroseal maintains its integrity both of strength and resiliency indefinitely, much longer than the life of the rest 10 of the shoe materials.

I claim:

1. A welt insole for use in the manufacture of welt boots and shoes, comprising an insole blank of one material and a preformed sewing rib of different material having an integral attaching flange secured to the marginal portion of the insole, said rib being of resilient plastic material, and having its upper portion of greater thickness than at the base of the rib adjacent 15 said flange.

2. A welt insole for use in the manufacture of welt boots and shoes, comprising an unchanneled insole blank and a separate preformed sewing rib having an attaching flange adhesively 25 secured to the marginal portion of the insole, said rib being of resilient plastic material, and having the inner side face slanting upwardly and inwardly toward the center of the insole, and the outer face having a portion substantially 30 perpendicular to the insole.

3. A welt insole for use in the manufacture of welt boots and shoes, comprising an insole blank and a preformed sewing rib secured to the marginal portion of the insole, said rib being of 35 resilient plastic material, and having the inner side face slanting upwardly and inwardly toward the center of the insole, and the outer face having a portion substantially perpendicular to the insole, with the lower portion of the outer face 40 in the form of a fillet.

4. A preformed rib of stitchretaining permanently resilient plastic material, having a horizontal attaching flange integral therewith, the inner face of the rib slanting over a portion of 45 said flange, and the outer face of the rib having a substantial portion of its length perpendicular to the flange, and the lower portion of the outer face in the form of a fillet merging with the attaching flange.

50

WALLACE C. WRIGHT.
